DOOR HOLDER

Edwin J. Sibley, Westbury, N. Y.

Application November 10, 1938, Serial No. 239,742

3 Claims. (Cl. 292—273)

This invention relates to improvements in door holders. The object of the invention is to provide a generally improved door holder of simple efficient design and sturdy compact construction.

5 In the accompanying drawing illustrating the invention

Fig. 1 is a view showing the door holder applied to a door the latter being shown in open position with parts broken away and parts in

10 section.

Fig. 2 is a plan view of Fig. 1.

Fig. 3 is a full size sectional view of the door holding mechanism, the section being taken substantially on the line 3—3 of Fig. 4.

15 Fig. 4 is another full size sectional view of the door holding mechanism taken substantially on the line 4—4 of Fig. 3.

Fig. 5 is a bottom view of parts shown in Fig. 4 looking in direction of the arrow 5.

20 In the drawing the reference numeral 10 designates the door frame and 11 the door hinged at 12. The door holder comprises a main bracket

13 which is let into a recess 14 in the top of the door being secured thereto by screws as indicated at 15. The bracket 13 comprises a channel 16 to which there is secured a housing which is made in two parts 17 and 18. The part 17 is secured to the bottom of the channel 16 by

25 screws as at 19 and forms a main support for the parts of the door holding mechanism. At the inner end of the bracket part 17 it forms an abutment 39 for the one end of a spring 20 the other end of which acts against a sliding abutment 21. The movement of the latter is limited by a screw 22 which projects into a slot 23

30 in the part 17. The latter also forms a bearing 24 for the vertically slideable door holding bolt 25. The latter is normally urged upwards into

35 door holding position by a spring 26 the tension of which may be regulated by a lever 27. The latter is pivoted at 28 on a screw which passes

40 through the parts 17 and 18, see Fig. 5. The lever rests upon a pin 29 in the bracket, being held against said pin by the spring. The lever

45 may be raised by means of an adjusting screw 30 which has a tapered head 31 adapted to engage the lever 27 to raise or lower the same in an obvious manner whereby to adjust the pressure of the spring 26.

50 The bolt 25 has a tapered head 32 adapted to be engaged by a sliding catch 33 which slides in the channel 16 and is provided with a cam surface 34 so that the catch can pass in over and depress the bolt and catch the head of the lat-

55 ter in a recess 35 in the catch. The latter is

pivoted at 36 to an arm 37 the other end of which is pivoted to a plate 38 secured to the door casing 11 as shown.

Figs. 1 and 2 show the door in open position. It will be seen that in this position the door is normally held firmly by the engagement of the catch 33 with the bolt 25. When however undue strain is exerted to close the door, the catch 33 will be moved outward in the channel 16 and automatically depress the bolt 25 and the door 10 may then be closed. The degree of holding power is controlled by adjusting the spring by the screw 30.

When free opening and closing of the door is desired the bolt may be moved down into 15 inaction position by means of a locking lever 40 which is pivoted upon a screw 41 and extends into a slot 42 in the bolt. The locking lever is engaged by a rotatable latch bolt 44 which is operable from the outside by a control knob 45. 20 In Figure 4 the latch bolt 44 is turned so that the locking lever is moved up into a recess 46 in the bolt. Consequently the holding bolt can move up into door holding position by the spring 26. When however the latch bolt is rotated 180° 25 by the knob 45, the locking lever is depressed and moves the holding bolt 25 down against the pressure of the spring. The holding bolt is now no longer free to move up into door holding position and the door may be freely opened and 30 closed. The spring 20 serves as a shock absorber against the slam of the sliding catch 23 when the door is opened and the catch is moved in over the holding bolt 25.

When the parts are assembled the bracket part 35 18 fits against the part 17 as shown in Figure 5 to form a housing and the spring 20 is covered by a plate 60. The two screws 28 and 41 hold the parts together. A cover plate 50, Fig. 3, completes the installation of the door holder and 40 provides a neat finished appearance.

The door holder may be used for either right or left hand doors as well as for double acting doors when desired.

In operation the door holding bolt 24 may be 45 in its lower or in its upper position depending upon the position of the recess 46 in the latch bolt. If the latter is turned as in Fig. 4, the holding bolt 25 will project upwards into the channel 16 and will then be engaged by the 50 sliding catch 33 to automatically hold the door in open position. If the holding bolt should have been moved into its lower inactive position, it may be raised after the door is opened by merely turning the knob 45 as to bring the recess 55

46 lowermost. Again, with the door in open position and held by the bolt 25 the latter may be withdrawn from the sliding catch 33 by turning the knob 45 to bring the recess 46 uppermost.

5 Thus the door holder may be easily manipulated to suit local conditions and requirements. The door holder includes therefore mechanism whereby the holding bolt will automatically be engaged by the sliding catch to hold the door under normal conditions, yet yield to free the door under excessive strain. By operating the knob 45 the holding bolt may be permanently or temporarily held in lowered inactive position or be left free to engage the sliding catch.

10 15 I claim—

1. A door holder comprising a guide structure and including a channel means for attaching the same to the top edge of a door, a catch slidably movable in the channel, an arm having one end 20 pivoted to said catch, means for pivoting the opposite end to the door casing, a bolt in said guide structure, a spring for moving said bolt into an operative position within the channel to engage said sliding catch in the position corresponding 25 to the open position of the door, means enclosed in the channel for cushioning the movement of the catch into open door position, a lever in said guide structure for moving said bolt into an inactive position against the said spring and for releasing the bolt to be actuated by said spring, a rotatable member for operating said lever and a knob connected to said rotatable member for manually operating the same.

2. A door holder comprising a guide structure 30 including a channel means for attaching the

same to the top edge of a door, a housing secured to the channel below the same, a vertically movable bolt in the housing, a spring for moving said bolt to project into the channel from below, a catch slidably movable within the channel and adapted to be engaged by said bolt in the position corresponding to the open position of the door, means within said housing for locking the bolt in inactive position below the channel against the said spring and for releasing the bolt to be 10 moved by the spring, means for actuating said locking and releasing means and an arm pivotally connected to the said catch and to the door casing.

3. A door holder comprising a guide structure 15 including a channel, a catch slidably movable within the channel, an arm pivotally connected to said catch, a housing secured to said channel within the door, a vertically movable bolt in said housing, a spring for moving said bolt up into the 20 channel in the path of said catch to engage the same in the position corresponding to the open position of the door, means in said channel for cushioning the movement of the catch into open door position, a lever pivoted in said housing and 25 engaging said bolt to move it into an operative position to be actuated by the spring or into an inoperative locked position against the spring, a rotatable member in said housing for actuating said lever, a knob for actuating said rotatable 30 member, a lever for supporting said spring in normally operative position and means for adjusting the position of said last named lever to regulate the tension of the spring.
